UNITED STATES PATENT OFFICE

165,303

HOLDER FOR GLASSES

Bruce A. Rogers and Joseph W. Doblin,
New York, N. Y.

Application October 3, 1950, Serial No. 12,438

Term of patent 14 years

(Cl. D44—7)

To all whom it may concern:

Be it known that we, Bruce A. Rogers and Joseph W. Doblin, citizens of the United States of America and residents of New York city, county of New York, and State of New York, have invented a new, original, and ornamental Design for a Holder for Glasses, of which the following is a specification, reference being had to the accompanying drawing, forming part thereof.

Fig. 1 is a perspective view of a holder for glasses, showing our new design.

Fig. 2 is a top plan view of the same.

We claim:

The ornamental design for a holder for glasses, substantially as shown.

BRUCE A. ROGERS.
JOSEPH W. DOBLIN.
